HOIST ATTACHMENT FOR TRACTORS

William C. Lathers, Jr., Madison, Wis.

Application September 11, 1948, Serial No. 48,857

9 Claims. (Cl. 212—8)

1

This invention relates to a hoist attachment for tractors.

The present invention is an improvement upon the subject matter of my United States Patent No. 2,470,857, issued May 24, 1949, and entitled "Hoisting Attachments for Motor Driven Vehicles, Such as Tractors."

It is a primary object of the invention to provide a hoisting attachment having exceptional versatility when attached to a tractor, supporting its load directly from the ground, but operable for the transportation of such load under tractor guidance in any direction, and also operable to deliver or remove the load from a truck or the interior of a building without having the vehicle enter the building, and to raise and lower the load from the ground to heights much greater than those possible through the use of my previous apparatus, the load being moved over two distinctly different fulcrums and shifted from one to the other automatically according to requirements.

The manner in which these and other objects of the invention are achieved will appear more particularly from the following disclosure of my invention with reference to the accompanying drawings, in which:

Fig. 1 is a view in side elevation of a device embodying my invention.

Fig. 2 is a view shown in plan of the device shown in Fig. 1.

The tractor 3 may be of any usual or desired type. It is supported by axles 4 from wheels 5. It has at 6 a power take-off from which a flexibly jointed and telescopically extensible coupling 7 leads to a winch drum 8 which is a part of my invention.

The particular tractor disclosed happens to have a bracket at 9 to which I pivotally connect by pintle bolts 10 the base portions 11 of a frame which comprises a tower for my hoist. The only other connections made to the tractor comprise anchor clamps 12 which are attached to any suitable part such as differential or axle housing 13.

As already indicated, the base portion 11 of the hoist frame is pivotally connected with the tractor for oscillatory movement in a vertical plane only. In all other directions of movement, it is constrained to move with the tractor. At its outer end, the cross bar 14 of the frame base is supported by a pair of spaced caster wheels 15 which carry the load without interfering in any manner with freedom of tractor movement.

Erected on the base 11 are the upwardly con-

2

verging bars 16 and 17 which are joined on the top of the derrick-like frame by caps at 18 which are spanned by the pintle bolt 19 upon which an intermediate portion of a boom 20 is pivoted or cradled. The derrick tower may be reinforced in any desired manner by cross bracing at 21, or otherwise.

The winch drum 8, already referred to, is preferably mounted in the derrick tower. Wound thereon is a cable 23 which leads around a sheave 24 in the inner end of the boom and thence around another sheave at 25 in the outer end of the boom. At its free end portion 26, the cable carries a stop collar 27 incapable of passing about sheave 25, being too large to pass between the sheave and the stop bolt 28. Beyond this collar 27, the cable terminates in any suitable load sustaining fitting, such as the hook 29 which may be engaged with a load diagrammatically illustrated at 30.

The derrick or tower is desirably inclined somewhat rearwardly above the caster wheels so that it will never tend to overturn toward the tractor. However, it is counter-balanced in any desired degree by tension springs 31 which are connected from the frame members 16 to the anchorage clamps 12 through the intervening turnbuckles 32 which provide for adjustment. Outward oscillation of the top of the tower in opposition to the tension of springs 31 is limited by the chains 33, likewise connected to the brackets 12 and extending thence to connections near the top of the tower.

The free pivotal movement of the cradled boom 20 upon its fulcrum pin 19 is limited at any desired point by connecting one or more chains 35 from the inner end of the boom to hooks at 36 upon the tower, with which selected links at the lower end of the chains are selectively engaged. Ordinarily, the chain will be so adjusted that the free outer end of the boom cannot descend substantially below the horizontal position of the boom as illustrated in Fig. 1. In this position, the tractor may be backed up to guide the free end of the boom into the open door of a building or into the open rear end of a truck or other place heretofore accessible only with difficulty. Even with the free end of the boom in any such relatively inaccessible place, it is a simple matter to hoist a weight such as that shown at 30 by attaching the hook 29 thereto, or in any other manner coupling the load with the cable, and starting the hoisting drum or winch 8 upon which the cable is wound. The controls for the hoist are not illustrated, since the tractor itself is ordi-

narily supplied with controls for its power take-off, and these may be used to operate the hoist.

With the load elevated above the ground, or floor, or truck bed, it may be carried from point to point simply by operating a tractor in the same manner as if my improved apparatus were not attached thereto, the caster wheels beneath the hoist permitting great freedom of tractor manipulation.

Assuming that after the boom 20 has cleared the door of the building or truck from which the load has been lifted and withdrawn, and assuming it is now desired to raise the load to some higher elevation, it is only necessary that the winch drum be operated for such additional amount as will cause the stop collar 21 to engage the free end of the boom, thereby arresting relative movement of the rope 23 respecting the boom. From this point on, the further winding of the rope on the winch drum will tilt the boom itself toward the dotted line position indicated in Fig. 1, thereby further raising the weight or load.

When it is desired to lower the load, the release of the winch drum will first permit the boom to drop to the limit of movement accommodated by chains 35, and hereupon the boom will remain stationary while the load continues to descend, the cable 23 paying through the sheaves 24 and 25 until the load reaches the desired level.

In addition to enabling my hoist to reach into such inaccessible places as buildings and trucks, it will be observed that the horizontal rearward projection of the boom in the full line position of Fig. 1 adapts it to operate over wells, mine shafts, or the like, which would be difficult of access if the cable sheave were located directly in the top of the tower or derrick.

For controlling the rate of paying out the rope or cable 23 from the winch drum 8, I desirably provide, within the reach of the tractor operator, a brake handle 37 which controls any suitable brake or drum. Details of the brake are not shown, these being no part of the present invention.

While the boom 20 has been illustrated as having the form of a truss, this being desirable, it will be understood that the invention is not at all limited in this regard.

I claim:

1. A hoist comprising the combination with a tower and a winch, of a boom pivotally cradled intermediate its ends upon the tower and provided at opposite sides of its pivot with sheaves, and a cable extending from the winch over the sheaves and provided with means engageable with the boom for limiting its withdrawing movement over the outermost sheave, said tower and one end of said boom being connected by an adjustably extensible and retractable tension member attached to the tower at a point spaced from said pivot.

2. A hoist adapted for connection with a tractor to be propelled and manipulated by the tractor operator, said hoist comprising a tower frame having a pivotal towing connection upon which said frame is vertically oscillatable, a caster-wheeled support for the frame rearwardly of said connection, and tractor-connected means for limiting the oscillation of said frame about said connection, a winch drum upon said tower frame and provided with a tractor-driven connection and a brake handle projecting forwardly to be accessible to a tractor operator, a line extending from

said drum, and a boom pivoted to said tower frame intermediate the ends of the boom and provided at opposite ends of the boom with sheaves over which said line is payed.

3. A hoist adapted for connection with a tractor to be propelled and manipulated by the tractor operator, said hoist comprising a tower frame having a pivotal towing connection upon which said frame is vertically oscillatable, a caster-wheeled support for the frame rearwardly of said connection, and tractor-connected means for limiting the oscillation of said frame about said connection, a winch drum upon said tower frame and provided with a tractor-driven connection and a brake handle projecting forwardly to be accessible to a tractor operator, a line extending from said drum, and a boom pivoted to said tower frame intermediate the ends of the boom and provided at opposite ends of the boom with sheaves over which said line is payed, the outer end of the boom and said line having interacting stop means limiting the withdrawal of the line over the sheave at the outer end of the boom.

4. A hoist attachment for a tractor designed for transportation and operation by the tractor operator, said attachment comprising a tower frame having towing pintles adapted for tractor connection, said tower frame being rearwardly inclined, laterally spaced caster wheels for the support of said tower frame rearwardly of said pintles, tractor anchorages, tension springs connected from the tower frame to said anchorages and counter-balancing the tower frame in its rearward inclination over said caster wheels, flexible connectors leading from said anchorages to an upper portion of the tower frame and limiting its rearward oscillation against tension of said springs, a winch drum mounted on the tower frame and provided with driving connections having a tractor power take-off coupling, a brake handle for said winch drum extending forwardly over said tractor to a position to be operated by the tractor operator, a line leading upwardly from said drum, a boom provided intermediate its end with a fulcrum on said tower frame, said boom having at its opposite ends first and second sheaves over which said line is payed, a tension connection limiting the oscillation of said boom about its fulcrum in a direction to lower its free end, and a stop connected with said line and engageable with the free end of the boom for the oscillation thereof in a direction to raise its free end.

5. A hoist adapted for connection with a tractor for propulsion over a supporting surface, said hoist comprising a tower frame having a pivotal towing connection upon which said frame is vertically oscillatable, a caster-wheeled support for the tower frame rearwardly of said connection, resilient tractor connected means for limiting the oscillation of said frame about said connection, a boom pivotally cradled intermediate its ends upon the tower whereby to extend one end thereof toward the tractor and the other outer end thereof in the opposite direction to receive a load, a sheave adjacent each end of said boom, a cable extending over said sheaves, a winch mounted to said tower in spaced relation to the pivot of the boom in position to receive and pay out said cable, and an adjustable tension member connected to the boom adjacent the tractor end thereof and connected to the tower adjacent the winch whereby upon assumption of a load upon the cable beyond the sheave on the outer end of the boom the weight of the load, boom and tower

may depress the vertically oscillatable frame in extension of said resilient means and bring the support into contact with the surface supporting the tractor.

6. A hoist adapted to be detachably connected to a tractor, said hoist comprising a tower, a winch on the tower, a boom pivoted intermediate its ends to the tower and having the greater portion of its weight at one side of the pivot to gravity bias the boom toward said side, an innermost and an outermost sheave at the inner and outer ends of the boom respectively and a cable extending from the winch over the sheaves, said cable having means engageable with the boom for limiting its withdrawing movement over the outermost sheave whereby to oscillate said boom about said pivot and against its bias.

7. The device of claim 6 in combination with an adjustable tension member connecting the tower and the boom near its innermost sheave to limit oscillation of the boom under its gravity bias.

8. A hoist adapted to be detachably connected to a tractor, said hoist comprising a tower having a pivotal towing connection upon which the tower is oscillatable, a winch on the tower and oscillatable therewith, a boom pivoted intermediate its ends to the tower, an innermost and an outermost sheave at the inner and outer ends

of the boom respectively, a cable extending from the winch over the sheaves, and means on said cable engageable with the boom for limiting withdrawing movement of the cable over the outermost sheave whereby to oscillate said boom on said pivot.

9. The device of claim 8 wherein the greater portion of the weight of the boom is at the same side of the pivot as the outermost sheave, said boom being provided with a tension member from a point near its innermost sheave to the tower.
